STEAM LOCOMOTIVE.

Application filed June 6, 1919. Serial No. 302,088.

This invention relates to steam locomotives, and more particularly to certain improvements in the equipment used for the production and distribution of superheat 5 for the development of power from steam or other gases in locomotives, ships, boilers, furnaces or other steam vapor or heat producing generators; the present improvements, however, being primarily designed 10 for the superheating of steam in locomotive and other boilers.

In the present state of the art relating to methods, processes and apparatus for superheating steam, particularly as used in locomotives, many difficulties have been encountered in practice, which, experience has demonstrated, may be attributed to the following causes:

The conducting means for the saturated 20 steam, occupies too much of the space within the boiler or other generator wherein the steam is generated; the steam as delivered by the boiler contains too much entrained water and moisture; entrained or condensed 25 water collects within the conducting conduits and the chambers wherein the saturated steam is to be superheated and results in obstructions or damage to the same; the superheater connections and the conduits 30 leading from the superheater to the boiler and to the engines or other points of utilization of the superheated steam are complicated in arrangement and occupy valuable space within the front end of the boiler, 35 thereby retarding and restricting the free flow of the heat producing gases; the superheated steam undergoes a serious reduction of pressure in comparison with the saturated steam pressure; and leakage, clogging and 40 overheating of the superheater elements, connections and fittings, particularly the superheater unit joints, is incurred resulting in structural deterioration and failure of the castings and other parts containing 45 both saturated and superheated steam or gases, due to expansion, contraction, or other causes.

Generically considered, it is therefore the primary object and purpose of the present 50 invention to minimize or entirely eliminate the undesirable features above enumerated, and to produce a more practical, effective and economical apparatus in design, con-

struction, application, operation and maintenance. These objects or purposes we propose and aim to accomplish without necessitating material alteration in the conventional locomotive or stationary boiler construction by: first, an arrangement of baffles at the boiler steam outlet to reduce entrainment of water with the steam; second, arranging the saturated steam conduit exteriorly instead of within the boiler and thereby increasing the boiler steam capacity and eliminating inaccessible pressure 55 joints; third, removing the superheater header and connecting parts from the front end or other boiler parts and thereby overcoming restrictions and making all parts 60 more accessible; fourth, providing means for trapping the condensed water in the saturated steam conduit or water entering the 65 conduit, due to leaky throttles, boiler priming and other causes before it reaches the superheater header and its adjunctive elements and reevaporating or otherwise disposing of the same; and fifth, removing the 70 conduit connections between the superheater header and the steam chests from within the front end or other boiler parts so as to permit 75 of the unrestricted flow of gases and provide greater accessibility.

Having the aforementioned objects in view, the present invention comprehends certain novel and improved combinations of 80 mechanical elements, and the structural characteristics thereof, as will be more fully developed in the following description and subsequently incorporated in the subjoined 85 claims.

Figure 1 is a side elevation of a locomotive boiler equipped with one embodiment of our improved superheater;

Figure 2 is an enlarged vertical transverse section through the front end of the boiler;

Figure 3 is a longitudinal section through the steam trap;

Figure 4 is a horizontal section through the superheater header taken on the line 4—4 of Figure 2;

Figure 5 is a detail section through the steam dome of the boiler and saturated steam pipe connection.

In the accompanying drawings, in Figure 1, we have, for the purpose of convenient 105 illustration, disclosed our invention as

adapted and applied to use in connection with a locomotive boiler designated generally by the numeral 10, and having the usual steam dome 11 and smoke box 12 into which the products of combustion are drawn through the fire-tubes indicated at 13, and ejected by a steam blast through the smoke stack 14.

In the preferred embodiment of our invention, the pipe or conduit 15 for saturated steam is arranged exteriorly of the boiler 10 above the same and is connected at one of its ends to the steam dome 11 as shown in detail in Figure 5. This connection includes a sleeve 16 riveted to the end of the pipe 15 and provided with a flange 17 through which passes a plurality of bolts 18 threaded in a plate 19 and into the wall of the steam dome. The end of the sleeve and the opposed face of the plate 19 are formed with the beveled seating surfaces 20 and 21 respectively for engagement with a gasket 22 having correspondingly beveled faces 23. A steam tight joint is thus produced between the steam pipe and the opening in the dome wall, when the clamping nuts 24 threaded on the bolts 18 are tightened against the face of the flange 17.

A casing 25 is arranged within the steam dome and is formed with an outlet neck 26 which is securely bolted as at 27 to the wall of the dome in coinciding axial relation to the steam conducting pipe 15. The top of the casing 25 is open and is formed with a shoulder 28 to receive a valve seat ring 29. The throttle valve includes a piston 30 working in a chamber 31, the walls of which are integrally connected to the casing 25 by means of a series of webs 32. The valve member 33 is connected to a boss 34, centrally formed on the piston 30, by means of a bolt 35, and is provided with a plurality of guide lugs 36 having sliding contact with the inner face of the ring 29. The valve member is formed with an annular beveled surface 37 for engagement with the similarly beveled seating face 38 of the ring 29. A rock shaft 39 is journaled in the walls of the steam dome 11 and the casing 25 and extends into the chamber 31. To this end of the rock shaft, one end of an arm 40 is fixed, the other end of said arm being connected by a link 41 to the piston 30. To the outer end of the rock shaft, an arm 42 is fixed and an operating rod 43 extending from the engineer's cab, is connected to said arm.

In order to prevent the water from being carried up and entering the opening of the throttle valve during priming, we have provided an arrangement of baffles within the steam dome. In the preferred embodiment of our invention, this baffle arrangement includes the disk shaped plates 105 and 106 which are alternately disposed with

relation to the annular ring shaped plates 107 and 108. The individual baffle plates are supported within the steam dome by means of spaced brackets 109 which are secured to the dome wall and whereby the several baffle plates are held in spaced parallel relation to each other. Each baffle plate is made up of a plurality of sections in order that the plates may be readily inserted and assembled within the boiler dome or removed therefrom.

The perimeter of each of the baffle disks 105 and 106 is downwardly turned or curved as shown at 110 so that each disk is in the form of a shallow inverted dish. The annular baffle plates 107 and 108 have their inner edges downwardly bent or curved as at 112 and disposed inwardly of the vertical plane of the edges 110 of the plates 105 and 106. The outer edges of the annular plates 107 and 108 have tight abutting contact against the wall of the steam dome while the outer edges of the plates 105 and 106 are spaced from said wall. Thus the steam is caused to ascend in a circuitous course around the edges of the baffle plates as indicated by the arrows while said plates effectively prevent the water rising within the dome and entering the throttle. The sectional construction of the baffle plates permits them to be readily removed so that they will not constitute an obstruction or in any way interfere with easy accessibility to the interior of the boiler. It is of course understood that the several baffle plates are properly cut or shaped so that they may be accurately fitted around the throttle valve casing.

The superheater header, generally indicated at 44 and to be presently described in detail, is also arranged exteriorly of the boiler and is suitably mounted upon the front end over an opening 45 in the top wall thereof. At its rear side, the header is centrally formed with an upstanding inlet neck 46 to which the downturned end of a trap 47 is connected by means of the clamping bolts 48 engaged through openings formed in the flanges 49 and 50 respectively. The inlet neck 46 is formed with a beveled seating face 51 with which the beveled face 53 of a gasket 52 is engaged.

The trap 47 is formed with an elongated well 54 extending transversely and having its bottom wall 55 inclined downwardly in each direction from the center of the trap. The condensed water which collects in this trap may be re-evaporated or drained from the same, its purpose being to prevent any considerable quantity of water passing over into the superheater header and elements at one time with resultant damage. A drain pipe 56 is connected to each end of the well 54 and is extended downwardly around the boiler. The lower ends of the drain pipes 130

may be equipped with valves 57 of any preferred type. The rear end of the trap is securely riveted to the forward end of the saturated steam pipe 15 and an obliquely inclined, transversely curved baffle web 58 is integrally formed with the top wall of the trap and projects downwardly therefrom above the center of the well 54. This baffle intercepts the globules of moisture or condensed water in the saturated steam and directs the same into the trap well so that the steam entering the header 44 will, to a large extent, be relieved of its water content. Such water as may enter the pipe 15 owing to leaky throttles, boiler priming and like causes, will of course be trapped and disposed of in a similar manner.

The superheater header as best illustrated in Figure 4 of the drawings, consists of a single metal casting, preferably of high grade grey iron. This header casting is formed with a longitudinal passage 59 along its rear side with which the neck 46 centrally communicates. At spaced intervals, 25 forwardly extending chambers or compartments 59' open into said passage. A second longitudinal passage 60 extends along the front side of the header and spaced rearwardly extending chambers or compartments 30 61 communicate with the latter passage and are alternately located relative to the chambers 59' which communicate with the passage 59. Pipes 62 are arranged exteriorly of the boiler and connected to the opposite 35 ends of the header in communication with the passage 60 and to the respective steam chests on opposite sides of the boiler. These connections consist of steam tight joints indicated at 63 and 64 respectively which are 40 similar to the joint connection between the trap and the inlet neck 46 heretofore described in detail.

A series of relatively large fire-tubes 65 extend between the tube sheets of the boiler. 45 These tubes receive the superheater units herein generally designated by the numeral 66. In the preferred embodiment of our invention, each of the superheater units consists of two pipes 67 and 68 respectively, the 50 pipe 67 being connected to a port 69, communicating with one of the saturated steam chambers 59' through the bottom wall of the header, while the pipe 68 is connected to a port 70 communicating with one of the superheated steam chambers 61.

The pipe 68 for conducting the superheated steam to the header is in a single straight length and extends into the fire-tube 65 in line with the axis thereof. The 60 pipe 67 for the saturated steam which also extends within the fire-tube, is turned around the pipe 68. The rear ends of the steam pipes are connected to each other by means of the usual return joint member not 65 shown.

Having above described the several structural features of our invention, its operation will be understood as follows:

When the throttle valve in the steam dome is opened, the flow of steam from the boiler 70 tends to lift or entrain the water with it, but is prevented from so doing, by the arrangement of baffles within the steam dome. The saturated steam enters the pipe 15 and in its travel therethrough to the header, the 75 water which has become entrained or condensed therein is removed by the trap 42 in the manner above explained. This steam, at a relatively low temperature enters the longitudinal passage 59 of the header and 80 the several chambers 59' in communication therewith. From these chambers, the saturated steam enters the pipes 67, and in passing through the pipes 67 the steam is raised to an exceedingly high temperature. With 85 increased velocity, the superheated steam flows through the straight pipes 68 and immediately enters the chambers 61 of the superheater header. The high velocity and the exceedingly high temperature of the superheated steam, makes such loss of heat as may occur in its passage through the header a negligible quantity so that the superheated steam will flow through the passage 60 and be delivered through the pipes 62 into the 90 working cylinders of the engine at a maximum velocity pressure, temperature and volume which may be utilized to the fullest extent and converted into useful work.

We desire to particularly call attention to the fact that as the saturated steam pipe and the superheater header are entirely removed from the interior of the boiler, much greater steam space capacity is afforded within the boiler than in the use of present day locomotive superheaters. Such arrangement also permits of a very free flow of the products of combustion, while the joint connections, where leakage is so liable to occur, are not subjected to an intense heat.

A further and very obvious advantage which is due to the exterior arrangement of the saturated steam pipe or conduit, resides in the fact that the inaccessible opening in the boiler tube sheet through which the pipe must be extended, is eliminated, such opening necessitating the use of steam tight joints that are quite difficult to make and maintain and which frequently leak and cause boiler and steam troubles.

Also the removal of the superheated steam conveying conduits between the superheater header and the engines or prime mover from the interior of the front end or boiler eliminates the necessity for making and maintaining joints between the superheated steam conveying conduits and the openings in the front end or other parts of boilers through which such conduits would pass. The exterior pipes or conduits 15 and 62 as well as 130

the header 44 are of course covered with a suitable insulating material. If desired, the insulation which is commonly provided upon locomotive boilers may be merely extended around the exterior conduits.

In the preceding description and the accompanying drawings we have disclosed a practical embodiment of the invention, which, however, may likewise be exemplified 10 in other alternative constructions. Accordingly the invention as herein claimed is to be considered as inclusive of all legitimate equivalents for the various elements employed as well as other contemplated arrangements thereof, which may satisfactorily accomplish the desired results.

We claim:

1. In a railway locomotive, a fire tube boiler having a smoke box at its forward 20 end and working cylinders on opposite sides thereof, a superheater header mounted externally of the smoke box, a supply pipe connection between the boiler and the superheater header arranged externally of the 25 boiler shell, superheater elements connected with the header extending through the smoke box and into the fire tubes of the boiler, and superheated steam supply connections between the header and said working cylinders.
2. In a railway locomotive, a fire tube boiler having a smoke box at its forward end and working cylinders on opposite sides thereof, a superheater header mounted externally of the smoke box, a supply pipe connection between the boiler and the superheater header arranged externally of the 35 boiler shell, superheater elements connected with the header extending through the smoke box and into the fire tubes of the boiler, and pipe connections between said 40 smoke box and into the fire tubes of the boiler, and pipe connections between said

header and the working cylinders arranged externally of the smoke box shell at either side thereof.

3. In a railway locomotive, a fire tube 45 boiler having a smoke box at its forward end and provided with a steam dome having a throttle valve therein and working cylinders at opposite sides of the smoke box, a superheater header mounted above the smoke box 50 externally thereof, superheater elements extending from said header through the smoke box into the boiler fire tubes, superheated steam supply connections between the header and the working cylinders arranged externally 55 of the smoke box, and a dry pipe extending longitudinally over the boiler shell and having externally accessible joint connections with the throttle valve and superheater header at its opposite ends. 60

4. In a railway locomotive, a fire tube boiler having a steam dome with a throttle valve therein and a smoke box at its forward end and working cylinders at opposite sides of said smoke box, a superheater header 65 mounted upon the upper side of the smoke box shell externally thereof, superheater elements connected with the header and extending through the smoke box into the boiler fire tubes, superheated steam supply 70 connections between said header and the working cylinders, and a sectional dry pipe extending longitudinally above the boiler shell and having externally accessible joint 75 connections at its opposite ends with the throttle valve and superheater header respectively.

In testimony that they claim the foregoing as their invention, they have signed their names hereunder.

JOHN E. MUHLFELD.
AUGUST G. SANDMAN.
